CAPE

Lyle C. Boyd, Miami, Fla.

Application August 2, 1952, Serial No. 20,887

Term of patent 14 years

(Cl. D3—3)

To all whom it may concern:

Be it known that I, Lyle C. Boyd, a citizen of the United States, residing at Miami, in the county of Dade and State of Florida, have invented a new, original, and ornamental Design for a Cape, of which the following is a specification, reference being had to the accompanying drawing, forming a part hereof.

I claim:

The ornamental design for a cape, substantially as shown.

LYLE C. BOYD.
